UNITED STATES PATENT OFFICE.

JAMES A. WALKER, OF LOS ANGELES, CALIFORNIA.

ROOF CONSTRUCTION.

1,124,563.

Specification of Letters Patent.

Patented Jan. 12, 1915.

Application filed April 15, 1914. Serial No. 832,045.

To all whom it may concern:

Be it known that I, JAMES A. WALKER, a citizen of the United States, residing at Los Angeles, in the county of Los Angeles and 5 State of California, have invented a new and useful Roof Construction, of which the following is a specification.

The present invention appertains to roof constructions, and aims to provide a novel 10 and improved joint for connection with the adjacent or meeting ends of the roof sections, such as of a portable house or cottage.

The present invention contemplates the provision of a peculiar joint for roof sections, which will enable the roof sections to contract and expand longitudinally, as well as laterally, to avoid a buckling or distorting of the roof boards.

Another object of the present invention is 20 to provide means for draining off any water that may seep or leak between the ends of the roof sections.

It is also within the scope of the present invention, to provide a device of this character, which will be comparatively simple, 25 compact, substantial, and inexpensive in construction, as well as being convenient, serviceable and efficient in its use.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

The invention has been illustrated in its 40 preferred embodiment in the accompanying drawings, wherein—

Figure 1 is a sectional view taken through the joint, parts being broken away, and the section being taken on the line 1—1 of Fig. 45 2. Fig. 2 is a side elevation of a fragmental portion of the roof illustrating the joint between two of the roof sections, portions being broken away. Fig. 3 is a bottom view 50 of the improved structure. Fig. 4 is an eaves view of the improved structure.

The roof, as illustrated, comprises sections 1, the meeting end portions of which have only been illustrated, inasmuch as the present invention relates more particularly 55 to the joint between the ends of the roof sections. Each roof section 1 embodies a series

of overlapping longitudinal roof boards 2, which are secured upon transverse cleats 3. Any number of these cleats 3 may be provided for each roof section, the end cleats 3 60 being spaced slightly from the adjacent ends of the roof boards 2, as seen in Fig. 4, whereby the ends of the roof boards will project or protrude beyond the cleats. Each of the roof boards 2 are secured upon corresponding cleats 3 by means of a single nail or securing element 4, which will enable the roof boards to expand and contract 65 transversely, without buckling or warping, and which will enable the roof sections to 70 expand and contract transversely without restraint. Each of the roof sections 1 further embodies a sheet of water proof material 5 of any suitable character secured upon the cleats 3 under the roof boards 2, whereby 75 a double assurance against leakage is provided. The roof structure is also a serviceable one, the water proof sheets 5 being protected by the roof boards 2, and the roof boards and water proofing sheets enabling 80 the roof to resist the penetration of heat to a better extent, as well as excluding the elements in a most effective manner.

The roof structure further includes a rafter 6 upon which the protruding ends of 85 the roof boards 2 of the roof sections are disposed, the end cleats 3 being disposed at the sides of the rafter 6. The rafter 6 may be mounted in place in the usual, or any other convenient manner. As will be ob- 90 vious, the rafter 6 underlies the meeting or adjacent ends of the roof boards 2, in order that the roof sections may expand and contract longitudinally upon the rafter 6, un- 95 der atmospheric changes.

The lower edges of the roof sections 1 are preferably connected by means of an eaves strip or bar 7 which extends under the lowermost roof boards 2. The strip or bar 7 is provided with mortises 7^a receiving the 100 projecting tenons 3^a of the lower ends of the cleats 3, whereby the lower ends of the cleats 3 and the eaves strip or bar 7 may be secured together. The lower end of the rafter 6 is provided with a tenon or projec- 105 tion 6^a underlying the eaves board or bar 7, and a bolt or other securing member 8 is engaged through the tenon or projection 6^a of the rafter, and the eaves board 7. The bolt 8 also preferably engages between the 110 adjacent ends of the lowermost roof boards 2.

A salient or cardinal feature of the present invention resides in the provision of a groove or channel 9 formed in the upper edge of the rafter 6 below the meeting ends 5 of the roof boards 2, and serving to catch any moisture or water which may leak between the ends of the roof boards. The ends of the waterproof sheets 5, as designated by the numeral 10, project over or into the 10 groove or channel 9 of the rafter, and may be overlapped, if desired. The end portions 10 of the sheets 5, will, when subject to the heat of the sun, or other conditions, drop into the groove or channel 9, to form a lining 15 therefor, or to provide a water channel of themselves for conducting the water downwardly which may leak through the joint between the roof boards.

To carry off the moisture or water from 20 the lower portion of the groove or channel 9, the rafter 6 is provided with a drain outlet or bore 11 extending from the lower portion of the groove or channel 9 to the lower edge of the rafter.

Another important feature of the present 25 invention resides in the provision of means for connecting the adjacent cleats 3 of the roof sections 1. To this end, there are provided a plurality of U-shaped yokes 12, bent 30 from bars or strips of metal, and straddling the rafter 6 from below, the ends of the yokes 12 being bent angularly, as at 13, and secured to the bottoms of the cleats 3. The yokes 12 will yieldably connect the end 35 cleats 3 of the roof sections, and will tend to hold the ends of the roof sections together, although the yokes will permit the roof sections to expand and contract longitudinally sufficiently under the various atmospheric changes.

The ends of the roof boards 2 are clamped 40 tightly upon the rafter 6, by means of wedges or keys 14 driven between the lower edge of the rafter 6 and the lower portions of the yokes 12, thus tending to draw the yokes 12 downwardly, to hold the roof boards tightly upon the rafter.

The present structure is adapted particularly for use on portable houses or cottages, 50 the several parts being readily assembled and separated, as will be obvious from the foregoing taken in connection with the drawing, without further comment. The roof sections may expand in either direction, without restriction beyond a desired amount.

Should any moisture seep or leak between

the ends of the roof boards 2, the moisture will be conducted downwardly along the upper edge of the rafter 6, either by the 60 edges 10 of the water proof sheets 5, or by the channel or groove 9, the water on reaching the lower end of the channel 9 being drained outwardly at the eaves through the passage or outlet 11. This is of particular advantage when the gap between the roof sections has been increased when the roof is very dry, so that a sudden rain shower would permit a small amount of moisture or rain to pass between the roof 65 boards, before the roof boards have expanded or swelled tightly together.

The present construction may not only be employed upon a roof, but may be utilized in other capacities, such as for a siding 75 structure, the rafter 6 being taken to represent a stud, and the parts 2, the clap boards.

As illustrated in Figs. 3 and 4, the eaves board 7 is preferably divided adjacent one 80 of the tenons 3^a, to enable the roof sections 1 to separate and come together at their meeting ends.

From the foregoing, the advantages and possibilities of the present invention will be obvious to those versed in the art, without 85 further description being necessary, it being noted that the objects aimed have been carried out satisfactorily by the provision of the structure herein disclosed.

Having thus described the invention, what 90 is claimed as new is:

In a roof construction, a rafter having a channel in its upper edge and having an outlet extending from the lower end portion of the channel to the lower edge of the rafter, roof sections including cleats at the sides of the rafter and longitudinal roof boards secured upon the cleats, the ends of the roof boards projecting beyond the cleats and resting upon the rafter, an eaves board 95 extending below the lower roof boards, the eaves board having mortises, the lower ends of the cleats having tenons engaging the mortises, and means for securing the lower end of the rafter and eaves board together, 100 the eaves board being divided adjacent one of the said tenons.

In testimony that I claim the foregoing as my own, I have hereto affixed my signature in the presence of two witnesses.

JAMES A. WALKER.
